UNITED STATES PATENT OFFICE.

RYOJIRO KIMURA, OF TOBACHO SHIMAGUN MIEKEN, JAPAN, ASSIGNOR TO THE TOBA DENKI SEISAKUSHO, OF SHIMAGUN MIEKEN, JAPAN, A CORPORATION OF JAPAN.

SLIP RINGS ON INDUCTION MOTORS.

Application filed May 8, 1920. Serial No. 379,941.

To all whom it may concern:

Be it known that I, RYOJIRO KIMURA, residing at No. 789 Tobacho Shimagun Mieken, Japan, have invented new and useful Improvements in Slip Rings on Induction Motors (for which I have filed an application in the Japanese Empire April 10, 1919, No. 45,760), of which the following is a specification.

10 My invention relates to slip rings for induction motors; and the object thereof is effectually to prevent sparks and reduce cost by simplifying the construction.

15 It consists in various features and combinations hereinafter described and more particularly claimed, reference being had to the accompanying drawings forming a part of this specification, in which,

20 Fig. 1 is a view in section, on several planes, the part above the axis of the main shaft being a section on the line AO; the part below thereof, a section on the line OJ; and the brush holder bracket, a section on the line OB, all on Fig. 2;

25 Fig. 2 also is a view in section, the left half being a section on the line DEFG and the right half that on the line HI, of Fig. 1;

Fig. 3 is a sectional elevation of the arm wheel with slip rings;

30 Fig. 4 is a plan of the whole;

Figs. 5 and 6 are, respectively, front and side elevations of the brush holder; and

Fig. 7 is a circuit diagram.

35 The same reference numbers represent the same or corresponding parts throughout all the figures.

According to my invention on the main shaft 1, on one side of the rotor, is keyed a wheel having radial arms 2. To the arms 2 are fixed by means of set screws 5, 5' two concentric slip rings 4, 4' with insulators 6 between the arms, rings, and heads of the set screws 5, 5' and the arms 2 having holes 16, thru which the said set screws pass, the hole being larger than the screw so that the screws do not touch the arms. In this way the slip rings are perfectly insulated from the arms 2. To the slip ring 4 is firmly fixed a pair of L-shaped short circuit leads 7; and to the slip ring 4', another pair of short circuit leads 7' of a similar shape but with shorter legs, respectively, by means of set screws 8 and 8'.

55 On the main shaft 1, is keyed a shift collar 11 in such a way that the collar can

slide backward and forward on the shaft. To the shift collar 11 are fixed two pairs of short circuit tongues 9, 9' arranged in such a way that they can be brought to contact respectively with the short circuit leads 7 60 and 7'. The shift collar 11 is provided with a groove 10 which engages two legs 19 of a brush holder bracket 18 to be described later on. Each of these legs has a pin 17 on the outside, which engages the free 65 end of one of two levers 13, the other end of which is firmly fixed to a shaft 21 which is rocked by a handle 20 supported by a bracket 15 firmly fixed to the bearing 14 of the motor. Thus by working the 70 handle 20 the shift collar 11 may be made to slide on the shaft to and fro through the levers 13 and the pins 17, and consequently the short circuit tongues 9, 9' also moved backward and forward. In Fig. 1, 75 in full lines, the shift collar 11 is shown at one of its extreme positions when the short circuit tongues 9, 9' are wholly out of contact with the short circuit leads 7, 7'; and the dotted lines in the same figure show the 80 shift collar at the other extreme position when the tongues are in contact with the leads.

The brush holder bracket 18 has a symmetrical construction and is shaped something like a saddle, having two legs 19, one on each side. The legs 19 of the brush holder bracket 18 are engaged by the 85 grooves 10 of the shift collar 11, while at its upper part the said bracket slides on 90 guide rods 22 firmly fixed to the bearing 14. Thus, if the handle is moved one way or the other the brush holder bracket slides to and fro on the guide rods 22 at the same time causing the shift collar 11 to slide correspondingly on the main shaft 1.

On each side of the brush holder bracket 18 are attached two brush holders 23, 23', respectively supporting brushes 25, 25', the said brush holders being secured to the said 100 bracket, as is shown in Figs. 5 and 6, by bolt 24, with an insulator between them. Brushes 25, 25' have each a hole into which is inserted a projecting rod 26. Each of the brushes 25, 25' at one end is engaged by a 105 spiral spring 29 provided in a spring holder 28, and it is thereby pressed in contact with the slip ring. The brushes 25 bear against the ring 4 and the brushes 25' against the ring 4'.

The wire connection, as is shown in the diagram is as follows: the wires (a) and (b) connect the windings of the rotor with the slip rings 4, 4', the wires (d) and (e) connect the slip ring 4, 4' with the rheostat 30, (c) is connected to the main shaft 1, utilizing the said shaft as a lead wire, and the wire (f) connects the brush holder bracket 18, which has electrical connection 10 with the main shaft, with the rheostat.

The operation is as follows: With the parts in the position they occupy when the short circuit tongues are disconnected from the short circuit leads, as shown in full 15 lines in Fig. 1, and the brushes, 25 and 25', in contact with the respective slip rings, 4 and 4', three phase alternating current is sent to the stator winding, and as a result of the revolving field set up by the stator 20 current, current is induced in the secondary which flows in one phase to the rheostat, through the lead wire (a), slip ring 4, brush 25 and lead wire (d); in the second phase through the lead wire (b), slip ring 25 25' 4', brush 25' and lead wire (e); and in the third phase through the main shaft (lead wire c), brush holder bracket 18 and lead wire (f). Then, remove all the resistance by moving the handle towards the position shown by dotted lines, the short circuit 30 tongues gradually approaching the leads 7, 7' and effecting contact therewith. At that time, however, the brushes 25, 25' are still in contact with the slip rings 4, 4'. 35 On continuing the movement of the handle the short circuit tongues move further towards the short circuit leads, until the whole surfaces of the two come into contact. At that moment the bottom of the slot 27 provided in the brush holder strikes against the projecting rod 26 and disconnects the brushes 25, 25' from the slip rings 4, 4'. 40

The main features of this invention consist in arranging the parts in such a way that 45 the brushes and the short circuit tongues move always in the same direction, that the brushes move into or out of contact with the slip rings perpendicularly and in a straight line motion, and that the short circuiting is effected before the brushes are 50 out of contact with the slip rings. Unlike slip rings hitherto used, in my invention

the surface of the slip rings and that of the brushes make no angle with each other in moving into or out of contact, the whole 55 surface contact is broken all at once in disconnecting as the brushes are maintained in perfect contact until short circuiting is completely effected. I thus minimize the wear of leads and prolong their life. Moreover, as the mechanism is very simple the first cost is low and the repair is easy. 60

Having thus described my invention, what I claim is:

1. The combination, in an induction motor, of a pair of rings; two sets of short circuit leads having their ends parallel to the main shaft; two sets of brushes movable into and out of contact with said rings; a pair of short circuit tongues movable into 70 and out of contact with said short circuit leads; and a bracket on which said brushes and said tongues are mounted, whereby they move in the same direction. 75

2. The combination, in an induction motor, of a pair of rings; two pairs of short circuit leads having their ends parallel to the main shaft; short circuit tongues; a shift collar to which said tongues are secured; two sets of brushes; a brush holder 80 bracket on said collar; and a handle for sliding collar on the main shaft. 85

3. The combination, in an induction motor, of a pair of rings; two pairs of short circuit leads having their ends parallel to the main shaft; short circuit tongues; a shift collar to which said tongues are secured; two sets of brushes; a brush holder bracket on said collar; and a handle for sliding collar on the main shaft. 90

4. An induction motor having slip rings, and coacting brushes, short circuiting means comprising shiftable tongues, said tongues and brushes moving in the same direction, 95 means for supporting the brushes to move parallel with the motor shaft axis and in a direction perpendicular to the plane of the contact surfaces of the rings, the tongues also being carried by said support, and 100 means for moving the brushes after the tongues reach circuit-closing position.

This 22nd day of March, 1920.

RYOJIRO KIMURA.
